UNITED STATES PATENT OFFICE.

ANTHONY CARLOZZO, OF YONKERS, NEW YORK.

HEEL FOR SHOES.

1,418,428.

Specification of Letters Patent. Patented June 6, 1922.

Application filed July 27, 1920. Serial No. 399,306.

To all whom it may concern:

Be it known that I, ANTHONY CARLOZZO, a subject of the King of Italy, residing in Yonkers, in the county of Westchester and 5 State of New York, have invented certain new and useful Improvements in Heels for Shoes, of which the following is a full, clear, and concise description.

My invention relates to heels for shoes, 10 and more particularly to the adaptation of such heels for the purpose of rendering them readily detachable, replaceable and interchangeable relatively to the shoe upon which they are worn.

15 More particularly stated, I seek to provide the rear end, or so-called heel portion, of the shoe sole with a special foundation for the heel, and to so form the heel as to enable it to be fitted upon and secured to this foundation, in such manner that the heel is 20 rigid and firm relatively to the foundation while the shoe is in active use by the wearer thereof, and yet so that the device can be quickly and easily dismembered whenever 25 for any reason it is desirable to remove the heel, and the same heel can be quickly and easily replaced, or another heel similarly formed may be readily replaced in its stead.

My invention further contemplates certain 30 advantageous changes in the construction of the heel, for the purpose of providing the heel with a detachable and replaceable tap of leather or rubber, as desired.

My invention further comprehends various 35 improvements in the heel and portions of the shoe associated with the heel.

My device may be used in connection with 40 heels made of either wood or metal, but is especially applicable to heels made of aluminum and hard wood. I do not wish to be limited, however, to any particular materials in instances where the selection of the material is a matter of choice or of mere mechanical skill.

45 Reference is made to the accompanying drawings forming a part of this specification, and in which like reference characters indicate like parts throughout the several figures.

50 Figure 1 is a longitudinal central section through a shoe provided with one form of shoe heel made in accordance with my invention and carrying a rubber tap.

Figure 2 is a section on the line 2—2 of 55 Figure 1, looking in the direction indicated by the arrow.

Figure 3 is a view partly a section on the line —3 of Figure 1, looking in the direction indicated by the arrow.

Figure 4 is a fragmentary section, somewhat similar to the bottom portion of Figure 1, but showing the heel as carrying a leather tap. 60

Figure 5 is a section on the line 5—5 of Figure 4, looking in the direction indicated by the arrows. 65

Figure 6 is a section somewhat similar to Figure 1, but showing the heel body as made of wood.

Figure 7 is an elevation of the heel appearing in Figure 6. 70

Figure 8 is a section on the line —8 of Figure 6, looking in the direction indicated by the arrow.

Figure 9 is a section on the line —9 of Figure 6, looking in the direction indicated by the arrow. 75

A heel body is shown at 10, and in this instance is made of light metal, preferably aluminum. This heel body is hollow, forming compartment 11. It has at its bottom a massive portion 12, the latter being provided with a shallow compartment 13 into which is neatly fitted a tap 14 of leather, held in position by screws 15. Fitting flatly 80 upon the leather tap 14 is another leather tap 16, held in position by screws 17. The tap 16, thus held in position, serves as a foundation and detachably mounted upon it is a rubber tap 18, held in position by screws 19. Thus the rubber tap 18 is readily 85 detached by simply removing the screws 19, and when worn out may be discarded and another tap substituted.

In some instances, instead of the rubber 90 tap just mentioned I employ a leather tap 20, held in position by nails 21, as shown in Figure 4.

It may readily be seen that with the tap 16 as a foundation, either a rubber tap 18 or a leather tap 20 may be used, as desired, and that a rubber tap may be taken off and a leather tap put on instead, or vice versa a rubber tap may be substituted in place of a leather tap. 100

The shoe heel as a whole is rendered easily detachable by means of the arrangement shown in Figures 1 to 3 inclusive. The upper portion of the heel body 10 is provided with a groove 22, extending around the top 110 of the compartment 11, this groove being bounded in part by an overhang 23, extend-

ing inwardly. The groove 22 is so formed and proportioned that an anchor plate 22 fits neatly into it. The anchor plate 24 is by means of short screws 25 or other appropriate fastenings mounted rigidly and firmly upon the heel portion 26 of a shoe sole 27. The anchor plate 24 is flat and straight and in this instance is made of metal, though it might in some instances be made of fiber or other tough sheet material suitable for the purpose.

The rear portion 26 of the sole being slightly rounded and the anchor plate being flat, as indicated in Figure 2, it follows that the edges of the anchor plate bear away slightly from the adjacent portion 26 of the sole. Thus there is a little clearance between each edge of the anchor plate and the adjacent portion 26 of the shoe sole.

20 The body member 10 is provided with a projecting lip 28, integral with it, and provided with a hole through which a short screw 29 extends, this screw also extending into the adjacent portion 26. This screw 25 prevents movement of the heel member 10 relatively to the rear portion 26 of the shoe sole, and in doing this prevents the heel as a whole from coming off so long as the screw 29 is in position.

30 In order to remove the heel the screw 29 is taken out and the heel as a whole is slid rearwardly, so that the anchor plate is virtually drawn out of the groove 22. This leaves the heel separate from the rest of the shoe. The same heel can be replaced, or another heel of the same kind can be substituted, and held in position as above described, by aid of the screw 29.

As may be noted from Figure 1, the lip 40 28 is pressed tightly against the adjacent portion 26 while the parts are in normal position. That is to say, the lip 28 extends into a plane coinciding with the general direction in which the anchor plate extends. On this 45 account, there is no crevice visible while the parts are in normal position. When, however, the screw 29 is taken out as above described, and the heel body is then displaced slightly to the rear, there is no difficulty in 50 causing the lip 28 to clear the end of the anchor plate, as the anchor plate is thin and more or less elastic, and the degree of distortion for effecting clearance is negligible.

In the form shown in Figures 6 to 9 inclusive, the heel body appears at 30 and is made of hard wood. It is provided at its top with a shallow concavity 31. At its bottom is a compartment 32, and fitted into the same is a tap 33. Upon this tap is another 55 tap 34. These taps are secured in position in the manner above described with reference to the taps 14 and 16, shown in Figures 1, 2 and 4. The taps 33 and 34 now serve as a foundation, and a tap 35, which may be

made of either rubber or leather, is detachably mounted in position upon this foundation in the same manner as the taps 18 and 20 above described.

The upper portion of the body member 30 is provided with a groove 36 and with an overhang 37 bounding this groove. An anchor plate 38 is secured by screws 39 to the rear portion 40 of a shoe sole 41, and is adapted to fit slidably into the groove 36, in the same manner that the anchor plate 24 fits 75 into the groove 22 as above described.

A retaining screw 42 is provided for preventing movement of the heel relatively to the sole, and by so doing for preventing the removal of the heel. The screw 42 extends through holes in the rear portion of the sole and the anchor plate 38. By taking out the retaining screw 42 and sliding the heel to the rearward, the heel is readily disengaged. By reversing the operation, the heel 85 is replaced.

I do not limit myself to the precise mechanism shown, as variations may be made therein without departing from my invention, the scope of which is commensurate 90 with my claims.

I claim—

1. In a device of the character described the combination of a shoe sole provided with a convex surface, an anchor plate mounted 95 upon said shoe sole and having in its entirety the form of a true plane, said anchor plate being provided with edges which, because of the flatness of the plate and the convexity of said convex surface, extend 100 slightly away from said convex surface, a heel member having a massive portion provided with a concave surface mating said convex surface of said shoe sole and further provided with a groove having the form of 105 a true plane and merging into the concavity of said concave surface, said anchor plate fitting into said groove in said heel member in order to hold said shoe sole and said heel member together, and means for preventing 110 displacement of said shoe sole and said heel member relatively to each other.

2. In a device of the character described the combination of a shoe sole provided with a convex surface, an anchor plate mounted 115 upon said shoe sole, said anchor plate being flat and provided with edges which, because of the flatness of the plate and the convexity of said convex surface extend slightly away from said convex surface, and a heel member 120 having a massive portion provided with a concave surface mating said convex surface of said sole and further provided with a groove merging into the concavity of said concave surface, said groove mating said 125 anchor plate in order to hold said shoe sole and said heel member together.

ANTHONY CARLOZZO.
